UNITED STATES PATENT OFFICE.

MORRISON R. SWAN, OF MANILLA, IOWA.

DESIGN FOR A BREASTPIN.

SPECIFICATION forming part of Design No. 30,714, dated May 9, 1899.

Application filed April 11, 1899. Serial No. 712,875. Term of patent 7 years.

To all whom it may concern:

Be it known that I, MORRISON R. SWAN, a citizen of the United States, residing at Manilla, in the county of Crawford and State of Iowa, have invented and produced a new and original Design for Breastpins; and I do declare the following to be a full, clear, and exact description of the same, reference being had to the accompanying drawing, forming a part thereof.

In the accompanying drawing I have shown a front view of a pin of my design.

As shown in the drawing, the leading or material feature of my design is a three-quarter view of Admiral Dewey, which picture is within a border formed by the steering-wheel of a vessel, and this again is finally bordered

by means of a rope-strand, as is shown. The outline of the wheel A is smaller than the border formed by the rope B, so that the handles C may properly project therefrom.

It is apparent that this design is also applicable to lockets, watch-casings, and other similar articles, and

Now, having described my said invention, what I claim as new, and desire to secure by United States Letters Patent, is—

The design for a breastpin as herein shown and described.

MORRISON R. SWAN.

In presence of—

KATE E. SWAN,
BEATRICE J. SWAN,
